SOLVENT REFINING OF MINERAL OIL

Louis A. Clarke, Fishkill, and Edwin C. Knowles,
Beacon, N. Y., assignors to The Texas Com-
pany, New York, N. Y., a corporation of Dela-
ware

No Drawing. Application October 9, 1935,
Serial No. 44,256

8 Claims. (Cl. 196—13)

This invention relates to refining hydrocarbon oil by solvent extraction.

The invention contemplates extracting hydrocarbon oil with ortho chlorphenol, or a solvent comprising ortho chlorphenol in the presence of a modifying solvent which is adapted to decrease the solvent action of ortho chlorphenol for mineral oil, and provide a solvent mixture having a satisfactory degree of selective action as between 10 constituents of the oil of differing viscosity indices.

More specifically, the invention contemplates extracting mineral lubricating oil with ortho chlorphenol in the presence of a modifying solvent compound, such as ethylene chlorhydrin, and also ethylene chlorhydrin saturated with hydrogen chloride. Extraction with the chlorphenol and modifying solvent mixture may be carried out in the presence of a diluent solvent 20 such as a light petroleum fraction of the character of propane.

In carrying out the extraction, the oil is brought into contact with the solvent mixture under conditions of temperature best adapted to effect 25 the particular degree of separation desired. After effecting intimate contact between solvent and oil, the mixture is allowed to separate into extract and raffinate phases. The extract phase contains relatively low viscosity index constitu- 30 ents and other undesired impurities of the oil dissolved in the bulk of the solvent liquid, while the raffinate phase comprises the relatively high viscosity index constituents of the oil mixed with some of the solvent. These phases are separated 35 from each other and the solvent liquid recovered therefrom.

In our co-pending application, Serial No. 44-254, filed October 9, 1935, we have described a process for solvent refining of mineral oil with 40 para chlorphenol and have there disclosed the unexpected improvement in the solvent refining action which is realized when extracting mineral oil with this latter compound.

We have found however that ortho chlorphenol 45 by itself is unsuitable as a separating solvent for mineral lubricating oil. This solvent is miscible with mineral lubricating oil at relatively low temperatures, and it also exerts a high solvent power upon both low and high viscosity index 50 constituents of mineral oil so that it is impossible to effect any substantial separation of the oil into its components. This high solvent power of ortho chlorphenol is also apparent when the solvent is used in admixture with its isomer, para 55 chlorphenol, so that when chlorphenol mixtures

containing the ortho isomer in substantial amount are used for extracting mineral lubricating oil relatively low yields of raffinate oils are obtained.

We have found that the addition of a modifying solvent, such as ethylene chlorhydrin, which seems to impart anti-solvent properties to the mixture, is of advantage in decreasing the otherwise high solvent power of the ortho isomer for the paraffinic or relatively high viscosity index constituents and permits realizing an improved 10 yield of raffinate oil. Chloracetic acid has also been found satisfactory as a modifying solvent, although ethylene chlorhydrin is preferable since it is a neutral substance and does not tend to react with the chlorphenol during continued use. 15

Ethylene chlorhydrin is therefore particularly suitable for this purpose and also when saturated with hydrogen chloride gas it provides a solvent mixture with ortho chlorphenol which is very effective in segregating from lubricating oil 20 stocks containing solid and semi-solid asphaltic constituents, lubricating oil fractions which are relatively low in residual carbon content.

We have discovered that the addition of a small amount of highly ionizable material to an extraction solvent increases the effectiveness of 25 the solvent in removing solid and semi-solid asphaltic material from residual lubricating oil stocks.

While ortho chlorphenol is itself highly ionizable, the addition of a non-acidic modifying anti-solvent such as ethylene chlorhydrin, tends to decrease the extractive power of the mixture for these asphaltic constituents. Accordingly, the addition of a small amount of hydrogen chloride 35 to the solvent mixture offsets any tendency of the added solvent to reduce the extractive power of the solvent mixture for these solid and semi-solid asphaltic bodies contained in the oil undergoing treatment. 40

The modifying antisolvent may be used in varying amounts up to as high as about 40% by volume of the chlorphenol, and when the mixture is saturated with hydrogen chloride it has relatively high solvent power for the asphaltic constituents of the oil. 45

Reference will now be made to the following experiments in which a heavy residual oil was extracted with a mixture of about equal parts of 50 ortho and para chlorphenol in the presence of chloracetic acid and also with the mixed chlorphenols in the presence of ethylene chlorhydrin saturated with hydrogen chloride gas. The modifying solvent in each instance was added to the 55

chlorphenol mixture in the proportion of 20% by volume of the phenol mixture.

In carrying out this experiment, the oil was first diluted with pentane in the proportion of 5 two parts of pentane to one part of the oil. The diluted oil was subjected to countercurrent contact with the modified solvent in an extraction tower. The extraction with chlorphenol and chloracetic acid was made at a temperature of 10 76° F., using the modified solvent in the proportion of 1.8 parts of solvent to 1 part of undiluted oil. The extraction with chlorphenol and ethylene chlorhydrin was made at 74° F., using a solvent ratio of two parts of modified solvent to 15 one part of undiluted oil.

The resulting extract and raffinate phases were separately removed and the solvent recovered therefrom by distillation. The following tabulation affords a comparison of the tests on the resulting raffinate in each case with the original oil.

	Residuum	Chlorphenol, chloracetic acid raffi- nate	Chlorphenol, ethylene chlorhydrin raffinate
25 Gravity, °A. P. I.	19.9	26.0	26.2
Saybolt Universal viscosity/210° F.	120	79	80
Viscosity index	69	95	104
30 Carbon residue, percent	5.6	1.75	1.5
Color	Black	Lt. green	Lt. green
Percent yield	100	66.2	66.0

It will be observed that in both instances a relatively high yield of raffinate oil, namely around 35 66%, was obtained. The raffinate in each case was light green in color and had a relatively low carbon content, namely 1.75 and 1.5% respectively, as compared with the carbon residue content of 5.6% in the case of the original oil. Both raffinates had a high viscosity index, of 95 and 104 respectively, as determined by the method of Dean and Davis.

The relatively low carbon residue content of 45 the foregoing raffinates obtained from a residual type of stock, indicates the advantage of the solvent mixture of this invention as a deasphaltizing solvent. The solvent mixture of our invention thus provides a combined separating and deasphaltizing solvent, and such that the asphaltic 50 bodies and the low viscosity index constituents may be removed simultaneously from the oil in a single treating operation, thus avoiding the necessity of subjecting the oil to individual operations 55 in which these undesired constituents of the oil are removed separately.

The results obtained with the solvent mixture 60 of our invention are comparable with and even superior to those obtained by the more usual type of operation in which the oil is deasphaltized in a preliminary or separate and distinct operation, and the asphalt free oil then subjected to separation with another solvent.

Reference has been specifically made in the 65 above experiment to diluting the oil undergoing treatment with pentane. It is contemplated however that other suitable diluents may be employed, as for example propane or butane or mixtures of light hydrocarbons of this character such 70 as in natural gasoline.

The temperatures, as well as the solvent proportions, may differ considerably from those specified above, and may be varied as desired in order to obtain the particular degree of solvent 75 refining action desired.

Obviously many modifications and variations of the invention as hereinbefore set forth may be made without departing from the spirit and scope thereof, and therefore only such limitations should be imposed as are indicated in the appended claims.

We claim:

1. The method of solvent refining residual lubricating oil fractions containing constituents of differing viscosity indices as well as dark-colored and residual carbon-forming bodies which comprises extracting the oil with a solvent mixture comprising ortho- and para-chlorphenol in about equal proportion and chloracetic acid, the chloracetic acid constituting around 20% or more of the phenol mixture, forming an extract phase comprising low viscosity index constituents together with dark-colored and residual carbon-forming bodies dissolved in the solvent, and a raffinate phase containing relatively high viscosity index constituents of light color and of low residual carbon content, and separating the two phases.

2. The method of solvent refining residual lubricating oil fractions containing constituents of 25 differing viscosity indices as well as dark-colored and residual carbon-forming bodies which comprises extracting the oil with a solvent mixture comprising ortho- and para-chlorphenol in about equal proportion and ethylene chlorhydrin saturated with hydrogen chloride gas, the ethylene chlorhydrin constituting around 20% or more of the phenol mixture, forming an extract phase comprising low viscosity index constituents together with dark-colored and residual carbon-forming bodies dissolved in the solvent, and a raffinate phase containing relatively high viscosity index constituents of light color and of low residual carbon content, and separating the 30 two phases.

3. The method according to claim 1 in which the residual lubricating oil fraction undergoing treatment is diluted with a light petroleum fraction.

4. The method according to claim 2 in which the residual lubricating oil fraction undergoing treatment is diluted with a light petroleum fraction.

5. In the manufacture of relatively light-colored lubricating oil of low residual carbon content from a petroleum residue by extraction with a monochlorphenol mixture containing a sufficiently large proportion of the ortho isomer such that the mixture exerts substantial solvent action upon high as well as substantially complete 55 solvent action upon low viscosity index constituents of the oil, the steps comprising extracting the residue with said chlorphenol mixture containing a high proportion of the ortho isomer in the presence of an auxiliary solvent comprising 60 chloracetic acid in an amount sufficient to decrease the solvent action of the ortho isomer upon the high viscosity index constituents of the oil without substantially reducing the solvent capacity of the solvent mixture for asphaltic 65 constituents of the oil, forming an extract phase comprising low viscosity index constituents together with dark-colored and residual carbon-forming bodies dissolved in the solvent, and a raffinate phase containing high viscosity index constituents of light color and of low residual carbon content, and separating the two phases.

6. In the manufacture of relatively light-colored lubricating oil of low residual carbon con- 75

tent from a petroleum residue by extraction with a monochlorophenol mixture containing a sufficiently large proportion of the ortho isomer such that the mixture exerts substantial solvent action upon high as well as substantially complete solvent action upon low viscosity index constituents of the oil, the steps comprising extracting the residue with said chlorphenol mixture containing a high proportion of the ortho isomer in the presence of an auxiliary solvent comprising ethylene chlorhydrin saturated with hydrogen chloride in an amount sufficient to decrease the solvent action of the ortho isomer upon the high viscosity index constituents of the oil without substantially reducing the solvent capacity of the solvent mixture for asphaltic constituents of the oil, forming an extract phase comprising low viscosity index constituents together with dark-colored and residual carbon-forming bodies dissolved in the solvent, and a raffinate phase containing high viscosity index constituents of light color and of low residual carbon content, and separating the two phases.

7. In the manufacture of relatively light colored lubricating oil of low residual carbon content

from a petroleum residue by extraction with a monochlorophenol mixture containing a sufficiently large proportion of the ortho isomer such that the mixture exerts substantial solvent action upon high as well as substantially complete solvent action upon low viscosity index constituents of the oil, the steps comprising extracting the residue with said chlorphenol mixture containing a high proportion of the ortho isomer in the presence of an auxiliary solvent selected from the group consisting of chloracetic acid and ethylene chlorhydrin saturated with hydrogen chloride, forming an extract phase comprising low viscosity index constituents together with dark-colored and residual carbon-forming bodies dissolved in the solvent and a raffinate phase containing high viscosity index constituents of light color and of low residual carbon content, and separating the two phases.

8. The method according to claim 7 in which the petroleum residue is extracted with the solvent mixture in the presence of a low-boiling petroleum hydrocarbon.
